UNITED STATES PATENT OFFICE.

HENRY SHERRILL, OF McMINNVILLE, TENNESSEE.

MUZZLE.

SPECIFICATION forming part of Letters Patent No. 430,547, dated June 17, 1890.

Application filed August 17, 1889. Serial No. 321,090. (Model.)

To all whom it may concern:

Be it known that I, HENRY SHERRILL, a citizen of the United States, residing at McMinnville, in the county of Warren and State of Tennessee, have invented a new and useful Muzzle, of which the following is a specification.

My invention relates to improvements in grazing-muzzles; and it consists in certain novel features hereinafter described and claimed.

In the accompanying drawings, Figure 1 is a perspective view showing my improved muzzle in its operative position. Figs. 2 and 3 are side views on a larger scale, showing the gate raised and lowered, respectively. Fig. 4 is a rear view.

In carrying out my invention I employ a ring or loop A, provided with the bails B at diametrically-opposite points and a lug or stop C above the said bails. The securing strap or rope by which the muzzle is attached to the animal's head is secured to the bails B, and the stop C serves to limit the movement of the gate, as will be hereinafter referred to. A leather ring or cushion D is secured to and concentrically within the ring A and bears against the head of the animal, so as to prevent chafing of the same and also insure the proper fitting of the muzzle. A slight distance in advance of the ring A, I arrange a ring E, within which I secure a cushion F, which may be of rope or leather, and is intended to prevent the nose of the animal being chafed by the muzzle. This ring E is secured to the ring A and held in a proper position by the securing-wires G, extending between the two rings, as shown.

The ring E is provided at diametrically-opposite points with the knobs or pins H, on which the gate I is pivoted. The said gate I is substantially triangular in shape and consists of the base-wire J, which is fulcrumed on the pins or knobs H, and the transverse and longitudinal wires K, secured to the said base-wire. The space above and below the gate is covered by the guard-frames L, which consist of the base-wires M, secured to and projecting forward from the ring E, and the connecting-wires N, secured to the ring E and the base-wires M.

On one side of the gate, near the fulcrum

of the same and at the upper edge thereof, I provide the knob or pin O, to which one end of a lever P is pivoted, the said lever extending forward from the said pin or knob and projecting beyond the base, so that its outer end will strike against the ground when the animal lowers its head. The lever is provided with a rearwardly-extending arm Q, which passes through the guide loops R on the side of the muzzle, and thereby prevents the lever swinging laterally from the muzzle. A link S is fulcrumed at its lower end on a pin or knob T, projecting from the lower guard-frame L, and has its upper end pivoted to the lever T, so that when the said lever is pushed upward by its contact with the ground it will also be given a slight outward curved motion, and the gate consequently swung over the upper guard-frame, so as to permit the animal to feed.

From the foregoing description, taken in connection with the accompanying drawings, it will be seen that I have provided a muzzle which is very simple in its construction, and which can therefore be manufactured and sold at a slight cost. The muzzle is applied to the head of the animal by passing the securing-rope attached to the bails B over the head of the animal, and when the animal raises its head the weight of the gate will cause it to fall, and thereby cover the central open space of the device and prevent the animal biting other stock or feeding from fruit-trees, as will be readily understood. When the animal lowers its head, however, the end of the lever P strikes against the ground, as hereinbefore stated, and the gate is thereby raised, as above described. When the gate is raised, it strikes against the lug or stop C, and is thereby prevented from swinging upward so far as not to fall when the animal again lowers its head.

The advantages of my device are thought to be obvious from the foregoing description, and further comment thereon is deemed unnecessary.

Having thus described my invention, what I claim, and desire to secure by Letters Patent, is—

1. A grazing-muzzle consisting of a supporting-ring having a stop on its upper side, upper and lower stationary guard-frames, and a

swinging gate resting normally between the guard-frames and adapted to swing over the upper guard-frame and impinge against the stop, as set forth.

5 2. A grazing-muzzle consisting, essentially, of the stationary guard-frames L and the gate fulcrumed at a point between the said guard-frames and adapted to swing over the upper guard-frame, as set forth.

10 3. In a muzzle, the combination of the ring E, the guard-frames projecting therefrom, the gate fulcrumed on the said ring E, the lever pivoted to the gate above the fulcrum of the same, and the link having its upper end pivoted to the lever and its lower end pivoted on the lower guard-frame, as set forth.

4. The combination of the rings A E, provided with guides on their sides, the guard-frames projecting from the ring E, the gate

20 pivoted to the ring E, the lever pivoted to the gate and having an arm projecting through

the guides, and the link pivoted to the lever and the lower guard-frame, as set forth.

5. In a grazing-muzzle, the rigid segmental-shaped frames L, located at the top and bottom and separated at their meeting inner edges in the center of the muzzle by an opening, which is sufficiently large for the animal to graze, and a gravity-gate pivoted intermediate of the guard-frames and adapted to normally cover the grazing-opening, said gate being larger than the guard-frames, so that it can be pushed up over the top guard-frame, and thus expose the central grazing-opening, as set forth.

In testimony that I claim the foregoing as my own I have hereto affixed my signature in presence of two witnesses.

HENRY SHERRILL.
